UNITED STATES PATENT OFFICE.

ALFRED GOODFELLOW, OF COATESVILLE, PENNSYLVANIA, ASSIGNOR TO CHARLES L. HUSTON, OF COATESVILLE, PENNSYLVANIA.

FINE ADJUSTMENT AND ALIGNMENT FOR APPROACH TABLES.

Application filed January 22, 1923. Serial No. 614,149.

My invention relates to the feeding mechanisms and to aligning devices for metal plates which are being transferred to operating tools or to other feeding devices.

5 The main purpose of my invention is to arrange for engagement with the plate at separated points by preferably magnetic grips forming parts of independent adjusting devices capable of use to align the plate or to feed the plate, securing more accurate alignment and better fine adjustment of the angular and lateral positions of the plate than are otherwise available.

10 Also to provide a comprehensive adjustment between the delivery end of a transfer table and a carrier capable of maintaining an initial exact alignment and placing of the plate.

15 Also to align or center a plate upon any feed or transfer table for whatever purpose, including cooperation with trimming shears or other operating tools.

20 Also to use the preferably magnetic holding devices and feeding mechanism by which the accurate alignment and fine adjustment are secured to hold the plate accurately in position while it is being gripped by the holding devices of a drag feed or carrier, in order that the alignment and adjustment secured may be maintained by the auxiliary feed.

25 Also to combine the advantages of exact and accurate mechanism for initially placing the plate with positive mechanism for gripping and guiding the plate at spaced points along the length of the plate so as to maintain the positioning of the plate secured.

30 Also to provide a fine feed using electromagnet clutches or grips which lie normally well below the lower face of the plate but which automatically lift to contact when energized fitting and following the contour of the plate.

35 Also to use a screw-operated drag for fine adjustment and alignment in conjunction with a roller feed for rapid adjustment, to obtain the maximum benefits from both and to use the roller support comprising part of the major adjustment to carry the plate during the movement of the fine adjustment.

40 Also to apply independent fine feed devices at different parts of a roll table so that they can be operated together in the same direction

for adjustment and together in opposite directions or separately for alignment. 55

Further purposes will appear in the specification and in the claims.

I have preferred to illustrate my invention by but one of the forms in which it may be applied, with some variations in the mechanism which can be used, selecting a form which is practical, efficient and highly satisfactory and which at the same time well illustrates the principles of my invention.

50 Figure 1 is a top plan view, largely diagrammatic, showing the preferred form of my invention with associated parts.

Figure 2 is an enlarged view corresponding generally with a portion of Figure 1 but different in detail.

70 Figure 3 is a section of Figure 2 upon line 3—3 of Figure 2.

Figure 4 is a section of part of the longitudinal carrier mechanism seen in Figures 1 and 2, comprising an electromagnetic drag. 75

Figure 5 is a top plan view of one of the adjusting and aligning devices seen in Figure 2.

80 Figure 6 is a side elevation of the structure seen in Figure 5.

Figure 7 is a side elevation of a detail of a structure which may be used in connection with Figures 11—14.

85 Figure 8 is a top plan view of another form of electromagnetic drag.

Figure 9 is a fragmentary side elevation, partly in vertical section, of the structure of Figure 8.

90 Figure 10 is a fragmentary end elevation of the structure of Figures 9 and 10.

Figures 11, 12, 13 and 14 are diagrammatic views showing different roll tables and devices fed by them, to which my invention may be applied.

95 In the handling of thick sheet metal such as is acted upon by hydraulic machines, many efforts have been made to avoid excessive hand movement and to provide complete effective and satisfactory mechanical devices for this purpose. While the shifting of the plates easily and rapidly over long distances by roller feed tables has been accomplished freely and manipulating devices are available for rapid and considerable angular turning of the plate upon the feed rollers, the 100 finer adjustments of the movement of the

105

plate and final alignment of the plates by slight angular movements have not correspondingly progressed. As a result, the final exact positioning of the plate, where accuracy is required, has necessitated hand work which is slow and laborious and at times also dangerous.

10 The best illustration of my invention is in connection with feeding devices to serve hydraulic shears and I have therefore illustrated it in that connection though I recognize that it has many other uses.

15 In carrying out the broad idea of cooperating lateral and longitudinal plate feeds intended finally to provide for the successive coincident shearings of sections of the sides of the metal plate, perfect positioning and alignment of the plate prior to the first cut and the maintenance of this alignment become of 20 first importance.

25 Two shears intended for synchronous action upon opposite sides of the same plate are shown diagrammatically at 10, 11, with right- and left-hand screw adjusting mechanism 12 for moving them toward each other to set the width to which the plate is cut. The two ends of each shear are synchronized by common knife operating mechanism connecting the plungers of cylinders 13, 14, 13', 14' in each shear and the two shears are hydraulically synchronized by being fed from different high pressure cylinders 15, 16 for shear 10, and 17, 18 for shear 11, all operated by the same intensifier. A shear of this character, having coincident operation on opposite edges of the plate with provision for cutting off the scrap so that the plate can be fed successively for other operations is shown in an application filed by Charles L. Huston for 35 40 Facing shears for cutting heavy metal plate, Ser. No. 576,998, filed July 24, 1922.

45 Transfer connections for feeding metal plate from the mill through the cutting shears, shear rolls, transfer rolls and various forms of roll or carrier devices to some form of shear are of course old. The connections which I have shown are largely old but contain new constructions not of my invention, in the carrier structure by which the plate is supported and moved to and between the shears and by which alignment secured is maintained.

55 Beginning with the roll table 19 from the plate mill I have illustrated in Figure 1 a conventional course of the plate through a shear 20 to shear rolls 21, serving also shear 22, and thence by roll table 23 and transfer table 24 to the carrier 25 upon which the plate is deposited from the transfer table and by 60 which it is carried to the shears and through between them. That this may be greatly varied, with lateral transfer, where the course of the plate from the mill is not in direct line with the carrier (parallel to the carrier or otherwise) and omitting the lateral transfer

where the paths are in line, but with fine adjustment and alignment in either case, is intended to be made clear by a few diagrammatic illustrations in Figures 11-14 from a number of arrangements familiar to those skilled in this art. The paths of the plate are parallel in Figures 11 and 12, with lateral transfer of the plate, while in Figures 13 and 14 their paths are in line and the plate passes to the carrier without need for any considerable lateral movement.

75 In these four figures, the roll tables at the mill are seen at 19', 19², the shears for the ends of the plate at 20', 22' (one only in Figure 13), the shear table or a table capable of 80 similar work at 21', 21² and roll tables 23', 23² in Figures 11, 12, 13 and 14. Diagrammatic transfer tables are shown at 24' in Figures 11 and 12 and casters 23², serving in part the place of a roll table are shown in 85 Figure 11. In all of these figures, as in Figure 1, roll tables, such as 21, 21² comprising rolls, each larger at one end than at the other and alternating in position may be rotated at the same speed and in the same direction 90 to feed the plate as on an ordinary roll table of straight rolls, or at different speed or direction to rotate the plate in horizontal planes.

95 In all of the figures the carrier shown represents one form only among many which may be used. It comprises a plurality of electromagnetic clutches or gripping devices, here electromagnets 26 supported in holders 27 which are adapted to slide in guides 28 upon the opposite sides of a channel 28' whose base 28² rests upon any beam or other support 28³.

100 The holders with their enclosed magnets represent independently-movable gripping devices which may be moved lengthwise of the guides at the same speed to engage different parts of the length of the plate, so as to maintain its alignment and unite the pulling force of two or more devices, or independently at the same or at different speeds and in different directions wholly independently of each other to operate upon different plates or different parts of plates where desired.

110 The electromagnets 26 are shown as vertically movable within the holders in order that their poles may lie well below the plates when de-energized but will lift into plate engagement when energized and will conform to the under surface of the plates. The poles project through thrust-receiving cover plates 29. The electromagnets are flanged at 26² to limit the upward movement 115 and are magnetized by windings 30 which are connected in series or in parallel as preferred and receive current through collector arms 31, 31'. The arms for different magnets are preferably supplied with current 120 125 130

from separate trolley wires in order that any magnet may be energized while the current is cut off from the other or others. Three are shown, though the number in use would probably much exceed this.

5 As will be recognized the broader aspects of my invention do not require that the gripping mechanism be electromagnetic, but this is so much the better form of grip that I have 10 illustrated two types of it to show that where the electromagnetic grip is used my invention is also independent of the detail of it.

15 In Figures 8, 9 and 10 the second form is shown in which the gripping electromagnet 26' is supported upon a frame 27' movable within the guide 28' and itself carrying the trolley contacts 31'.

20 The casing 32 of the gripping electromagnet is tapered at the sides at 32' and is extended at front and back at 32' where it is apertured at 32' to receive tubular extensions 33 which form guides for the casing, permitting and guiding vertical movement of the casing with respect to the frame.

25 The interiors 33' of the tubular members 33 act as guides for the pins 34 whose lower ends are enlarged to form armatures 34' for the lifting solenoidal magnets 35 by which the gripping electromagnet is lifted into position to engage with the plate.

30 The pins 34 carry cross bars 36 which pass through slots in the sides of the tubular extensions 33 and extend beyond the sides of the tubular parts to sustain the weight of 35 the entire casing 32 within which the gripping electromagnet is carried.

35 The gripping electromagnet is energized by a coil 37 and the various parts are supported and protected by plates 38', 38'.

40 The electric connections indicated are such as to pass the electric current through the lifting and gripping coils in parallel with the result that when electrical connection is made energization of the solenoidal coils 45 will lift the armatures and hence the cross bars 36 raising the gripping electromagnet into contact with the plate, after which the gripping magnet will follow vertical movement of the plate. Obviously for the purpose of cutting off the current from the solenoidal coils when the gripping magnet has 50 taken hold, the lifting and gripping coils may be separately energized and controlled.

55 Whatever the form used the holders and their electromagnetic grips or clutches may be drawn lengthwise of the carrier by cables 39, of which one is shown as connected with each grip to operate it alone. The other 60 cables pass through and are supported by the several holders. From the holders shown the cable passes about one of the idlers 40 and a tension shive wheel 41, then forwardly through the bottom of the channel about the idler 45, motor driven drum 44 and back 65 over one of the idlers 43 to connect with the

other end of the holder after passing over one of the shives 42. The connections of the others are similar to this.

On each side of the carrier is a roller-supporting frame 46, 47 whose rollers 48 are intended to take the weight of the plate as it is being dragged along by one or more of the carrier grips. 70

The transfer table described comprises a plurality of tilting sections 49, each carrying rollers 50, provided with gear teeth and intermediate gears 51. One of these gears 51 is driven by gears 52, 53, pairs of gears 54, 54', 55, 55', and gear 56 from shaft 57 of motor 58 so as to maintain constant driving connection. The sections are pivoted upon shaft 59. 75

The end of the table adjoining the carrier is lifted and lowered by means of rods 60 pivoted in the table at one end and at the other end in bearings 61 upon beam 62 extending the length of the table. The beam is mounted near its center upon the plunger 63 of a hydraulic cylinder 64 by which the beam is raised and lowered. 80

Within the zone of the transverse feed table, in front of the sections 49 are located beams 65 which rest at one end upon the beam 62 and at the other end have bearings at 66 in any suitable support. At an intermediate point in the length of the beams 65 I mount upon them a beam 67 connected by pivoted rods 68 with cross heads 69 movable in guides within one of the roller-supporting frames. The cross heads 69 carry rollers 50' at their upper ends which assist in the support of the plate while the adjoining end of the transfer table is raised and which drop with it to allow the plate to rest upon the rollers 48. 90

The ends of the transfer table sections adjacent to the carrier are adapted to rest within recesses not shown in the frame 47 so as to allow the plate to come to position upon the rollers 48. 100

As thus described plates from any suitable rolling mill or storage are delivered to the transfer table and are adapted to be placed by it upon the carrier to be moved to and through the shears. 110

My invention is intended to fit in with such a laterally extending transfer table, if it be needed, or with a more direct supply of plates from the mill, omitting lateral transfer (Figures 13 and 14, for example) and to be used with or without a connecting carrier, or with any table or delivery mechanism where fine adjustment of the final position of the plate or alignment of the plate is needed. 115

The operating devices by which I adjust and align are shown in sets of three, 70, 71 and 72, in some of the figures, and in sets of two elsewhere, though any number may be used for which there is room. Each one of the set is separate and distinct from the other and comprises a grip or clutch 73 along with operating mechanism by which it can be moved in 120 125 130

either direction. Hence any two can be moved in the same direction or in opposite directions. One grip can be held energized but stationary while another or others swing the plate about it. They are shown to advantage in Figures 5 and 6 in which the actual grips or clutches for engagement with the plate are like those used for the drag-conveyor but the operating mechanism is different.

While I show three adjusting and aligning devices, two are located near the opposite sides of the table so as to make it possible to handle with them plates of the full length for which the table is intended, and the third is placed between them but at different distances from them so as to connect with the nearer device for short plates and with the farther device for intermediate lengths.

The grips or clutches comprise electromagnets 74, arranged in series or in parallel as preferred, within frames 75 movable within guides 76. The second form of grip, Figures 8-10, or any other could be used here. The frames are rigidly connected with or may be integral with nuts 77 for threaded operating rods 78 resting in bearings 79 and turned by gears 80. The gears are driven by spur gears 81 upon shafts 82 carrying gears 83 at their opposite ends, and these last gears are shown as driven by spur gear 84 upon the armature shafts of motors 85. The current is supplied to the conductors 86 from any suitable source not shown preferably selectively, so that one or two can be energized and the other or others remain inactive.

Because it is desirable to use the rollers of the transfer table, as idle rollers merely for the support of the plate, in order that it may be moved by my adjusting and aligning devices with a minimum of energy (and in preference to supplying special rollers) any of the interconnecting gears between the table rollers 50 and the motor may be shifted to disconnect the gearing where desired, avoiding the necessity for turning all of the gearing and the motor armature by these devices. I show such a mechanism in brackets 87 swinging about the shaft 59 and carrying gear 53 so that by swinging of the bracket to a different position the connection between this gear and the gear above it may be interrupted.

In the various figures, I have shown not only supplemental rollers 50 which were adapted to lift and lower in conjunction with the lifting and lowering of the transfer table, but have shown rollers 50' at points where there is no transfer table and in figures where the plate is delivered from the rollers in direct line to the side cutting shears or other hydraulic tools. These rollers 50' are so placed as to rotate in planes transverse to the length of the carrier and are intended to represent any devices by which the plate can be lifted free from the rollers 48 of the carrier or

rolls upon which the plate may be supported so as to facilitate lateral movement of the plate for centering or alignment of the plate.

For the purpose merely of completeness in illustration I have shown in Figure 7 one way in which rollers 50' can be lifted and lowered whether they be inserted within openings in the carrier frame or be separate and distinct from the carrier frame or from the frames of rolls or rollers from which they are intended to take the weight of the plate.

In Figure 7 the rollers 50' are carried by plungers 88 operating in guides 89 and moved by fluid pressure operating upon pistons 90 within cylinders 91, fed by pipes 92, controlled in any suitable manner.

Any appropriate supplemental system of rollers adapted to lift the plate and to facilitate the transverse movement of the plate may be used in conjunction with my fine adjustment devices to provide for centering or alignment at any point in the travel of the plate securing the same ease of movement as is secured by supporting the plate upon a transverse table while making the mechanism wholly independent of the presence or absence of lateral transfer of the plate.

In some of the figures I have shown sets of fine adjustment mechanism on opposite sides of the carrier for the purpose merely of indicating that the operation of the device may take place in any position at which the plate is accessible and that devices on opposite sides of the plate may be used to advantage.

The capabilities of both forms of electromagnet of dropping out of the way of the plate when not in use and of lifting and lowering without losing their hold on the plate permit the transfer of heavy plates in the planes of the plates without rubbing against the de-energized magnetic poles when the device is not in use and enable the magnet to adapt itself somewhat to a plate surface which is not wholly smooth and uniform but varies from the intended plane, securing reliable contact with the plate and maximum traction. It also avoids strain between the magnet and plate which would cause undue friction against the guiding surfaces.

In order that the electromagnets may not be in the way of the plates under normal circumstances and may not be engaged by them except when desired but may come into firm contact with the plates in operation, I place the electromagnets normally well below the lower surface of the plates. The location of the flanges of the electromagnets in the first form well below the cover plates and the movement given the casing of the electromagnet in the second form with respect to the frame by which it is carried give the necessary freedom for upward movement in both forms so that the electromagnets lie well below the plate when not in use and lift into contact conforming to the surface of the plate.

when in use. The cover plate in the first form and the tubular guide members in the second form support the magnets against the transverse pull when the magnets are operating to move the plates.

In operation, the plate receives its approximate setting by operation of the transfer table or of the feeding rolls, as the case may be, and is preferably supported above the rolls or rollers rotating in longitudinal planes upon rolls or rollers rotating in planes at an angle and preferably at a right angle to the length of the plate. It needs centering or alignment to bring its length directly in line with the shears. If the transfer table be used, the left end of the table is in raised position so that the plate is supported upon it and upon the rollers 50 which lift with the table and lie beyond the carrier. Otherwise it will be supported upon some such devices as rollers 50'. The fine adjustment may swing with the table, where this is used, but need not do so, as the comparatively slight vertical movement of the table need not interfere with the electromagnets lifting to make proper contact with the plate. Provided the plate be a long one, where there are three adjusting devices the end adjustments will be used. If a very short one, the two adjustments nearer the center of Figure 1 will be used. If a moderate length plate, the plate will be run out on the transfer table to lie over the adjustment nearest the observer in Figure 1 and the intermediate adjustment.

35 In any event, the proper electromagnets are energized to cause the cores to lift into engagement with the plate and the corresponding motors are operated to turn the threaded rods and move the plate, preferably first disconnecting one of the gears in the 40 train controlling the transfer table where this table is used so that the rollers of the transfer table may be used as idlers for this purpose.

45 If the electromagnets are moved in the same direction toward or from the carrier, the plate will be adjusted merely, but it may be aligned by operating one of the adjustments only while the other or others are de-energized; by operating one of the adjustments while the magnet of another is energized, but the adjustment is not operated so that the latter magnet acts to define a pivotal point; or by operating two of the adjustments in opposite directions.

The electromagnets of the carrier may be energized to make contact with the plate either before or after the plate is lowered into contact with the rollers on the two sides of the carrier. They may be given range of vertical movement to make effective contact in either case.

It will be obvious that there are many other forms in which my invention may be applied and which will suggest themselves

readily to others skilled in the art in view of the disclosure made herein. It is therefore my purpose to include herein all such other forms as come within the reasonable spirit and scope of my claims.

Having thus described my invention, what I claim as new and desire to secure by Letters Patent is:—

1. The method of adjusting or aligning a plate for delivery to a carrier by use of a transfer table, which consists in transferring the plate to the general position desired at a level above the carrier giving the plate fine adjustment by means separate from the transfer means while in its raised position to place the plate accurately above the carrier, and lowering the plate upon the carrier.

2. The method of adjusting or aligning a plate for delivery to a carrier, which consists in moving the plate to the general position desired at a level above the carrier, giving the plate fine adjustment by means separate from the moving means while in its raised position to place the plate accurately above the carrier, engaging the plate by clutch mechanism upon the carrier and lowering it upon the carrier.

3. The method of adjusting or aligning a plate for delivery to a carrier, which consists in moving the plate to the general position desired at a level above the carrier, giving the plate fine adjustment by means separate from the moving means while in its raised position to place the plate accurately above the carrier and lowering it upon the carrier.

4. The method of adjusting and aligning a plate for delivery to a carrier, which consists in moving the plate to the general position desired at a level above the carrier, giving the plate fine adjustment by means separate from the moving means while in its raised position to place the plate accurately above the carrier, lowering the plate and engaging the plate near its end by grip mechanism upon the carrier while in the lowered position, and gripping it at points near the ends of the plate to maintain it in aligned position.

5. The method of aligning a plate with respect to a conveyor which consists in supporting the plate over the conveyor upon rollers rotatable in planes transverse to the conveyor, in aligning the plate while so located, and in lowering the plate upon the conveyor.

6. The method of aligning a plate with respect to a conveyor which consists in supporting the plate over the conveyor upon rollers rotatable in planes transverse to the conveyor, in aligning the plate while so located and in lowering the plate upon the conveyor and engaging the conveyor with the plate.

7. The method of aligning and conveying a plate which consists in providing a conveyor having rotatable plate supports turning in planes parallel with the length of the conveyor, in supporting the plate above the level of the conveyor upon rotatable devices movable in a plane perpendicular to the length of the conveyor, in aligning the plate while so supported, in lowering the plate upon the supporting device of the conveyor and in maintaining the alignment by holding devices between the conveyor and plate.
8. A table provided with rotary devices adapted to support heavy metal plate, in combination with two independent electro-magnetic gripping fine adjusting means for the plate located in proximity to opposite sides of the table and separately and independently engaging and moving the plate.
9. A table adapted to handle heavy metal plates, a carrier at the delivery end of the table, a plurality of gripping devices in the carrier capable of operating upon the same plate, a plurality of gripping devices on the table adjacent opposite sides of the table adapted to engage the plate, means for causing the gripping devices to engage the plate and fine adjustment means for moving the gripping devices within the table to adjust and align the plate over the carrier gripping devices.
10. A transfer table adapted to be raised and lowered, a carrier upon which a heavy

metal plate is adapted to be deposited by the transfer table, and fine adjusting mechanism for the plate adapted normally to lie below the lower surface of the plate when the table is in its lowest position and adapted to grip and move the plate for fine adjustment when the table is in raised position.

11. A carrier having rollers adapted to receive a heavy metal plate, gripping devices therein for moving the plate, a table at one end of the carrier adapted to deliver a plate above the carrier and to rest it upon the carrier, in combination with electro-magnetic grips, normally lying below the upper level of the table in the lowest position of the table and movable upwardly to grip the plate in the raised position of the table and fine adjustment connections for said grips to move them independently in order to adjust or align the plate.

12. A tool for operating upon heavy plate, a conveyor for the plate, feeding it to the tool, comprising roller supports for the plate and a drag and grips for engaging the plate, means for holding the plate above the conveyor but free from it and adapted to move freely in a direction lateral to the conveyor, fine adjusting means for aligning the plate with respect to the conveyor and means for placing the plate as thus aligned upon the conveyor.

ALFRED GOODFELLOW.
